UNITED STATES PATENT OFFICE.

WILLIAM A. KIRKPATRICK, OF SEATTLE, WASHINGTON.

WRENCH.

1,344,234.

Specification of Letters Patent. Patented June 22, 1920.

Application filed December 3, 1919. Serial No. 342,097.

To all whom it may concern:

Be it known that I, WILLIAM A. KIRKPATRICK, a citizen of the United States, residing at Seattle, in the county of King and State 5 of Washington, have invented certain new and useful Improvements in Wrenches, of which the following is a specification.

This invention relates to new improvements in wrenches.

10 The object of the invention is to provide a wrench so constructed that a greater pressure on the handle when turning a nut will cause a correspondingly greater action between the jaws to force the jaws in firmer 15 engagement with the nut.

The invention also comprehends improvements in the details of construction and operation which will be more particularly pointed out in the specification and claims.

20 In the drawings:

Figure 1 is a perspective view of the wrench.

Fig. 2 is a sectional view on the line 2—2 of Fig. 1.

25 Fig. 3 is a sectional view on line 3—3 of Fig. 1.

Fig. 4 is a side elevation with parts broken away, the jaws being open.

Fig. 5 is a view similar to Fig. 4 with the 30 jaws in closed position.

Fig. 6 is a disassembled perspective view of the jaws.

1 indicates a wrench handle formed with a bifurcated end portion 2, in which is mounted 35 the jaw members 3 and 4, the jaw member 3 being hereafter distinguished as the operating jaw and jaw member 4 as the sliding jaw.

The jaw members are mounted in the 40 bifurcated end for respective movement on pins 5 and 6 extending through and carried by the bifurcated ends.

The jaw members are formed of plates 7 and jaws 8, the jaws being formed with the 45 plates at one edge thereof and extending beyond one face of the plate so that, when the jaw members are assembled, the jaw will extend over the opposite plate so that both jaws will be in alinement.

50 The jaw member 3 has a transverse rib 10 which engages in a slot 11 and jaw member 4 has a transverse rib 12 which engages in the slot 13, so that the jaw member 4 is only permitted a transverse sliding motion with 55 respect to the operating jaw member.

The operating jaw member 3 is pivotally supported on the pin 5 and has a slot 14 concentric therewith, through which the pin 6 passes, the jaw member being adapted to rotate about pin 5 as is obvious. 60

The sliding jaw member has a slot 15 through which pin 5 passes which slot is parallel with the ribs 10 and 12. A slot 16 in the sliding jaw member receives pin 6 and registers with slot 14 in jaw member 3 65 at one point only, the point where pin 6 passes through the two slots.

Any movement of the operating jaw member about the pin 5 will cause a corresponding transverse sliding movement of the sliding jaw caused by the change in position of the pin 6 in the slots, the ribs 10 and 12 guiding the sliding jaw member. 70

In the use of the wrench the jaws in position as shown in Fig. 1 are placed over a 75 nut in the usual manner, the handle of the wrench is then moved to cause the jaws to move together as shown in Fig. 5. The jaws tighten on the nut before the limit of movement is reached and further movement of 80 the handle to turn the nut will cause a greater tightening motion of the jaws on the nut and prevent the jaws from slipping or marring the faces of the nut. 85

What I claim is:—

1. A wrench comprising a handle having a bifurcated end portion, an operating jaw member and a sliding jaw member, formed of plates adjacently disposed and mounted in the bifurcated end of the handle, the 90 plates having jaws formed thereon, each jaw extending over the adjacent plate so that the jaws are opposed and in line with one another, the plate of the operating jaw member having a hole and a slot therein the 95 slot being in the circumference of a circle with the hole as a center, the plate of the sliding jaw member having a recess to register with the hole, and a slot which partially registers with the slot of the operating jaw, 100 the operating jaw having a rib and groove formed therewith adapted to coact with a groove and a rib formed with the sliding jaw permitting respective movement between the jaws in line therewith, a pivot pin 105 mounted in the handle and extending through the recess in the sliding jaw and the hole in the operating jaw and another pin mounted in the handle extending through the slots in the operating and sliding jaws, 110

whereby a movement of the operating jaw around the pivot pin will open or close the jaws.

2. A wrench including a handle, an operating jaw member, a pivot for pivotally mounting said member in the handle, the said jaw member having a slot circumferentially disposed to the pivot, a sliding jaw member mounted in the handle having a 10 transverse slot and a longitudinal slot, the

transverse slot being adapted to permit movement of the pivot relative to the sliding jaw member and a pin passing through the longitudinal slot of the sliding jaw member and the slot of the operating jaw member whereby a movement of the handle about the pivot will cause a relative movement of the jaw members. 15

In testimony whereof I affix my signature.
WILLIAM A. KIRKPATRICK.
